Primary Examiner — Katrina A Betton

(74) *Attorney, Agent, or Firm* — Brooks Kushman P.C.

(57) **CLAIM**

The ornamental design for a truck bed cargo system, as shown and described.

DESCRIPTION

FIG. 1 is a rear, left perspective view of a truck bed cargo system in accordance with our design;

FIG. 2 is a rear perspective view thereof;

FIG. 3 is a right side view thereof;

FIG. 4 is a left side view thereof;

FIG. 5 is a top plan view thereof;

FIG. 6 is a rear view thereof;

FIG. 7 is a view of the truck bed cargo system on a truck;

FIG. 8 is a rear, left perspective view of a truck bed cargo system in accordance with our design;

FIG. 9 is a rear perspective view thereof;

FIG. 10 is a right side view thereof;

FIG. 11 is a left side view thereof;

FIG. 12 is a top plan view thereof;

FIG. 13 is a rear view thereof; and,

FIG. 14 is a view of the truck bed cargo system on a truck. The broken lines in the figures illustrate the environmental structure on which the truck cap assembly is used and form no part of the claimed design.

1 Claim, 14 Drawing Sheets
